UNITED STATES PATENT OFFICE.

FRANK KERN, OF MATTOON, ILLINOIS.

DESIGN FOR AN UNDERWAIST.

SPECIFICATION forming part of Design No. 26,574, dated January 26, 1897.

Application filed May 8, 1896. Serial No. 590,779. Term of patent 14 years.

To all whom it may concern:

Be it known that I, FRANK KERN, a citizen of the United States, residing at Mattoon, in the county of Coles and State of Illinois, have 5 invented and produced a new and original Design for Underwaists, of which the following is a specification, reference being had to the accompanying drawing, showing a part thereof.

- o The drawing represents a side elevation of an underwaist embodying my improved design.

The leading feature of my design consists of the curved shoulder-straps A, the lower 5 extremities of which extend downwardly below the waist-line. A prolongation of the shoulder-straps downwardly is effected by means of converging bands or tapes B, the straps and tapes forming in said view virtually an approximately elliptical conformation. Within the center of this elliptical opening is disposed the converging or V-shaped bands C, projecting downwardly within the opening to a point substantially opposite the waist-line, where they are provided with buttons D, substantially in a line with the buttons upon the lower ends of the shoulder-straps and upon the body of the waist at 5 the waist-line.

- o The body portion E of this skeleton underwaist is connected to the outer sides of the

shoulder-straps and passes around to the opposite shoulder-straps, where the body portion is similarly secured.

The usual stocking-supporter tape or band 35 G extends from the converging point of the V-shaped bands B, and the underwaist has in addition the usual buttons for securing the waist together after it has been put upon the wearer.

The general shape and design of the shoulder-straps, with the intermediate V-shaped supporting-bands and the lower prolongation of the shoulder-straps in the bands B, form an ornamental and graceful design and underwaist, the merits of which are meeting with very great success in the market.

I claim—

The design for an underwaist having the closed elliptical part A and the V-shaped termination B at the other end, and the intermediate V-shaped part C disposed toward the V-shaped end B, the two V-shaped parts being located one above the other in the same vertical plane, and arranged with their projecting points in the same direction.

In testimony whereof I affix my signature in the presence of two witnesses.

FRANK KERN.
